UNITED STATES PATENT OFFICE.

FREDRIK LJUNGSTRÖM, OF LIDINGON-BREVIK, ISIDOR BROBERG, OF TALLHYDDAN, SKARSATRA, AND ERIK OTTO ERIKSSON, OF ORMBUNKEN, BREVIK, LIDINGON, SWEDEN, ASSIGNEES TO AKTIEBOLAGET LJUNGSTRÖMS ANGTURBIN, OF STOCKHOLM, SWEDEN, A CORPORATION.

REVERSING DEVICE FOR TOOTHED GEARING.

1,388,351.

Specification of Letters Patent. Patented Aug. 23, 1921.

Application filed May 28, 1919. Serial No. 300,380.

To all whom it may concern:

Be it known that we, FREDRIK LJUNGSTRÖM, residing at Lidingon-Brevik, Sweden, ISIDOR BROBERG, residing at Tallhyddan, 5 Skarsatra, Sweden, and ERIK OTTO ERIKSSON, residing at Ormbunken, Brevik, Lidingon, Sweden, subjects of the King of Sweden, have invented new and useful Improvements in Reversing Devices for 10 Toothed Gearing, of which the following is a specification.

In toothed gearing provided with a reversing device and more especially in vehicle gearing said reversing device has been 15 generally so arranged as to have the reversing take place by an axial displacement of an additional toothed wheel, such displacement being effected manually. With this arrangement it has been often necessary to 20 use a friction coupling between the various parts of the gearing, in order to facilitate the engagement of the toothed wheels with each other, without subjecting them to breakage when coupling their teeth in incorrect 25 relative position.

When employing large gearings transmitting considerable amounts of power, the above mentioned design of gearing cannot be advantageously used, and other means for 30 effecting the reversal had to be devised, in order to prevent the gearing from being destroyed.

In accordance with the present invention, this object is attained by so connecting the 35 reversing device with the gearing or with the starting means for the driving fluid for the gearing that the reversing device cannot be operated as long as any one of the gear wheels is rotating, or as long as the driving 40 fluid is acting.

This may be obtained in the simplest possible manner as set forth in the following description, the reversing device being operated hydraulically, for example through the 45 medium of pistons operated by means of oil pressure; an operating lever or the like, by means of which the movement is effected, being locked as long as any one of the gear wheels is rotating.

50 Preferably an additional toothed wheel is employed in the reversing mechanism, the

same being movable in a radial direction and adapted to be thrown in and out of mesh between the driving and the driven gear wheels. By the present invention the axial 55 extension of the gearing is considerably reduced as compared with constructions employing wheels which are axially displaced, and as the additional toothed wheel requires only a small space to permit the same to be 60 thrown in and out of engagement, the whole gearing will be appreciably reduced in size.

The invention also includes an arrangement for obtaining such positions of the idle wheels to be thrown in engagement with each 65 other, that a tooth of one wheel is, at the moment of effecting the coupling, always situated opposite the tooth space of the other wheel. If the wheels are moved toward each other and their teeth are not in a position to permit a tooth of one wheel to engage 70 with the tooth space of the other wheel, then by my mechanism the first wheel is compelled to rotate under friction on the other wheel until tooth and tooth space are situated opposite each other. This result can be 75 advantageously obtained by using spiral cut wheels, as the engagement of such wheels will always occur at the point of tangency of the circles, so that a rotary movement of 80 one wheel does not bring about any change in the distance between the centers of the wheels.

An embodiment of the invention is shown in the accompanying drawings in which:— 85 Figure 1 is a diagrammatic view.

Fig. 2 is a similar view with certain added details shown in section.

Fig. 3 is a sectional view taken on the line 90 $a-a$ of Fig. 2.

Fig. 4 shows a detail of the mechanism shown in Fig. 2.

Fig. 5 is a detail sectional view of the controlling valve and its cylinder taken on line 95 $5-5$ of Fig. 7.

Fig. 6 is a similar view taken on line 6—6 of Fig. 7.

Fig. 7 is an axial section of the valve taken on line 7—7 of Figs. 5, 6 and 8.

Fig. 8 is a horizontal sectional view taken 100 on line 8—8 of Fig. 7.

Fig. 9 is a view similar to Fig. 7 but show-

ing the valve depressed to permit fluid from its interior to pass to the means for ascertaining whether the wheels are revolving, said section being taken on line 9—9 of 5 Fig. 10.

Fig. 10 is a horizontal sectional view taken on line 10—10 of Fig. 9.

Fig. 11 is an axial sectional view taken on line 11—11 of Figs. 12 and 13 and showing 10 the valve further depressed for admitting fluid to the cylinder which controls the unlocking and locking of the reversing gear shifting means.

Figs. 12 and 13 are horizontal sections 15 taken on lines 12—12 and 13—13 of Fig. 11.

Fig. 14 is an axial section taken on line 14—14 of Figs. 15 and 16 and showing the valve turned in a clock-wise direction to admit fluid to the cylinder which controls 20 the means for bringing the teeth of the gears into correct alinement for engagement, and to the cylinder which controls the means for shifting the reversing gear.

Figs. 15 and 16 are sections taken on lines 25 15—15 and 16—16 of Fig. 14.

Fig. 17 is a diagrammatic view of the valve and the cylinders.

Referring particularly to Fig. 1, 1 denotes a driving wheel and 2 a driven toothed wheel. 30 The wheel 1 is always supposed to rotate in the same direction, whereas the wheel 2 can rotate in either direction, that is to say forward, when it is driven directly from the wheel 1, or in the opposite direction when 35 driven from the wheel 1 through the medium of the intermediate wheel 3. 4, 5 and 6 designate the shafts of the wheels 1, 2 and 3 respectively.

Thus the wheels 2 and 3 are to be displaced when changing from forward to rearward movement or vice versa, such displacement being effected by means of the following mechanism.

In the position shown in the drawing, 40 wheel 2 is rotating backward. When a reversal is to take place, oil is introduced into the cylinder 7 under the piston 8 through the lower inlet 9, the said introduction of oil being effected upon the stopping 45 of all wheels by means of an arrangement shown in detail in Fig. 2. The piston 8 is then raised within the cylinder and thereby moves the stud 10 to the point 11, the shaft 13 being simultaneously rotated by means of 50 the crank 12. The cam 14 and the crank 15 are rigid with the shaft 13. When the latter is being rotated, the cam 14 raises the frame-work 16 together with the shaft 5 and the toothed wheel 2. On account of the 55 shape of the cam this does not, however, take place before the crank 12 has passed the intermediate position 17. The toothed wheel 3 is eccentrically journaled in the disk 18 and when the shaft 13 is turned, this disk

will be rotated by means of the crank 15 65 and the rod 19 during the movement 10—17, the toothed wheel 3 being thereby moved out of mesh with the toothed wheels 1 and 2. During the latter part of the reversing motion 17—11, the crank 15 is turned still more, 70 so that the pin 20 is displaced to the point 21, the pin 22 on the rod 19 to the point 23, the shaft 6 to the point 24, and this causes the wheel 3 to assume the position indicated by the dot- and dash lines in the 75 drawing. During the period of this latter movement, the cam 14 is turned so that the frame work 16 is raised to a position, wherein the axis of the shaft 5 is situated at a point 25. In this position of the shaft 5 the 80 toothed wheels 1 and 2 are in direct engagement with each other and the toothed wheel 3 is out of mesh.

In case the teeth of the wheels 1 and 2 have been brought in such relative positions, 85 when the tooth of the one wheel is not situated opposite the tooth space of the other wheel, a lever 26 automatically turns the toothed wheel 1 to a position suitable for engagement with the wheel 2. The lever 26 90 is also actuated by means of oil in a cylinder, provided with a piston, the said movement coacting with the other movement in such manner that the lever 26 will turn the wheel 1 at the right moment and through a sufficient angle of movement. The arrangement 95 will be described more in detail with reference to Fig. 2.

Now if it is desired to effect a backward motion of the wheel 1, the piston 8 is lowered, the wheel 2 being thereby first thrown out of mesh, whereupon the wheel 3 is thrown in engagement. If free running of the gearing is desired, the piston 8 is actuated so that the stud 10 will stop at 17. In 100 this position neither the wheel 2 nor the wheel 3 is in engagement with the wheel 1.

In Fig. 2 the same embodiment is illustrated as in Fig. 1, the same, however, being shown in detail. Fig. 2 particularly 110 illustrates the arrangement preventing reversing before all of the wheels contained in the gearing are standing still.

The reference characters common to both figures designate similar parts of the construction. In this case all of the oil cylinders are operated by means of a starting arm 30 which may be lowered as well as rotated. The starting arm is pivoted in the lug 33 of the piston slide valve 32 by means of a pin 31. The piston slide valve 32 may thus be rotated and brought up or down in the oil cylinder 34 by means of the arm 30. The walls of the piston slide valve and the cylinder are provided with passage ways, communicating with the various oil cylinders. By means of different movements of the starting arm 30, oil is introduced into the

various cylinders which are operated in the succession required for the reversal of the gearing.

This will be described more fully herein-
5 after with reference to Figs. 5, 6 and 7.

As indicated in the introduction of this specification, the reversing device has to be so connected with the gearing or with the starting means for the driving fluid, that the 10 reversing device cannot be brought into operation as long as any one of the wheels of the gearing is rotating.

In the embodiment illustrated, the arm 30 cannot be actuated before the wheels of the 15 gearing or any one of them has been stopped. This may be effected in the following manner.

56 denotes the starting lever for the driving fluid, for instance the starting lever of 20 the steam supply of a locomotive. As long as this lever 56 occupies such a position that the driving fluid is acting the arm 30 is locked and vice versa, when the arm 30 is in its operative position, starting of the driving 25 fluid cannot take place. This is accomplished by means of two stopping bolts 57, which in the normal positions of the handles, as shown in the drawing, are pushed into recesses in the operating lever at 58 and 59 respectively 30 by means of a spring disposed between the bolts.

In the operating lever, the recess 58 is situated in a spherical surface 60 and this recess is of such a depth that the left hand 35 bolt is locked in said recess in all positions of the lever 56 but the normal one, that is to say the position in which both stopping bolts are in the recesses. The same arrangement is provided for at 59 in the arm 56, and thus 40 only one of these two arms at one time may be turned from its normal position. Thus the oil operating lever 30 for the reversal of the gear wheels is locked on all occasions, when the driving fluid is acting. The arm 45 30 may be operated only when the starting handle 56 for the driving fluid occupies the position shown in Fig. 2, that is to say when the driving fluid is not acting and vice versa, the starting handle 56 may be dis- 50 placed from the position shown in the drawing and the motor started only when the arm 30 occupies its normal position, shown in the drawing.

Now, if reversing is to take place, for in- 55 stance, from forward to backward, that is to say, if the wheel 3 is to be thrown in mesh, such operation will be effected in the following manner.

To begin with the starting handle 56 for 60 the driving fluid has to be brought into the position shown in the drawing so as to cut off such fluid.

Then the arm 30 is turned around its pivot 31 by pressing down the handle. This arm 65 30 may be turned around the longitudinal

axis of the piston slide 32 in a clockwise as well as in a counter-clockwise direction; turning in the one direction brings about the reversal from forward to backward, in the other direction and from backward to forward. The arm cannot, however, be turned, 70 before the gear wheels are standing still as it may happen that the gear wheels continue to rotate after the cut-off of the driving fluid, particularly in vehicles the motion of which 75 is continued owing to inertia, such as locomotives.

To prevent the turning of the arm 30 before the gear wheels have come to rest, the 80 following arrangement has been provided.

When the arm 30 is turned about its pivot 31, the piston slide 32 is pressed down, oil being thereby admitted from a pressure-oil receptacle into two oil cylinders 73, the pistons 71 of which actuate the semi-circular 85 friction wheels 37 and 38 or other similar members so as to press them against frictional tracks 74 on the wheels 1 and 2. These disks are moved against the wheels 1 and 2 in an axial direction as shown, and 90 for this purpose they are beveled. If one or both of the wheels 1 and 2 is or are rotating at this time, the corresponding or both wheels 37 and 38 will be turned so that the studs 39 and 40 are displaced downward. 95

A pin 41 will also be moved downward, and this will cause a lever 42 to be turned so as to push up a rod 43. This rod 43 will in such case be introduced into a hole 44 in the starting lever 30, the latter being thereby locked so that it cannot be further operated or turned. Suitable means such as a spring 70, Fig. 3, inserted between the piston 71 and the fixed casing 72 tends to move the system 36-43 back into the position 100 shown in the drawing, thereby overcoming all friction. As mentioned, the arm 30 may be turned only in case all of the gear wheels are standing still. Assuming that this will at last be the case, then when the arm 30 is 110 pressed down on another trial, the rod 43 will not be lifted, and thus the arm 30 may be turned so as to effect the reversal.

The arm having been turned somewhat so as to move the boss 35^a of the arm 30 past the boss 35, the arm 30 may be pressed down farther until the piston 32 reaches the bottom of the cylinder 34. On this second movement downward, whether the arm has been turned to the right or the left, oil is 115 admitted under a piston-like end 45 of the spindle 46, which latter is lifted so that (see Fig. 4) the locking recess, 47 for "forward" movement or the recess 47^b for "backward" movement in a disk 48^a connected with the 120 toothed wheel 48 is released from the cylindrical pawl 47^a of the spindle 46. The continued movement of the arm 30, in the same direction, will then cause the valve 32 to open the oil supply to the lower part of 130

the cylinder 7, the said cylinder 7 effecting the coupling and uncoupling of the toothed wheel 3, as hereinbefore described with reference to Fig. 1.

- 5 When the piston slide valve 32 is again lifted, oil will be discharged from the space under the piston 45 which is brought back into its lower extreme position by means of the spring 75. A beveled toothed segment 10 49 is fixed to the shaft 13 and when the shaft is turned, the segment 49 drives a beveled gear 51 fixed to the lower end of a spindle 50. The spindle 51 is so proportioned relatively to the segment 49 that the spindle 50 15 can never turn more than half a revolution, in order that the locking device 47—47^a or 47^b—47^a shall fit in the two extreme positions. A wheel 52 fixed to the spindle 46 is driven by the wheel 48, the spindle 46 being 20 provided with a square-head adapted to be engaged by a crank handle (not shown).

The two recesses 47 and 47^b may be replaced by a single one. 47^c denotes a recess for free running.

- 25 The upper part of the spindle 46 coacts with the arm 30 which is provided with a ball-shaped end 76 that projects into a space provided between two guiding flanges 77 on the spindle 46. By this arrangement the 30 arm 30 cannot be brought back into its normal position before the locking of wheel 48 by means of the locking disk 48^a, the latter holding the spindle 46 in its raised position on all occasions when the reversing device 35 is not locked for forward, rearward or free running. The device not being locked, the spindle and consequently its point of connection with the arm 30 are raised, and the latter cannot then be brought back into 40 its normal position. Thus the device in question prevents the driver of the locomotive from admitting steam before the reversal has been completed.

The spindle 46 which is threaded at 53^a 45 is also provided with a nut 53 having a pointer 54 indicating the position held by the gearing, the said pointer 54 moving over a scale 54^a.

As it is of the utmost importance that 50 the wheels 1 and 3 are brought in such a position relatively to each other, when being thrown in mesh, that the teeth thereof fit exactly, the following arrangement has been provided which always places the wheels in 55 the position required.

A piston 61 moves within an oil cylinder 55 which also receives pressure-oil through the medium of the piston slide valve 32, when the latter is moved to the position in 60 which oil is admitted to the cylinder 7. The said piston 61 is provided with two levers 26, the points of which coact with locking rings 62 on the wheels 1 and 3, which locking rings are provided with the same number of teeth as the gear wheels 1 and 3. The

piston 61 is provided with a cross pin 63 projecting through slots 64 in the cylinder 55. A pressure spring 65 has one of its ends abutting against the ends of the cross pin 63 and its opposite end abutting against the bottom of the casing 66. The said spring tends to hold the piston 61 in its upper extreme position against the pressure of oil which is introduced into the space 67 within the casing 66.

The levers 26 are provided with cam surfaces 68 coacting with the edge of the opening 69 in such manner that the levers 26 are brought together and out of engagement with the locking rims 62 when there is no oil pressure in the space 67 and the piston is moved upward by the action of the spring 65.

When oil is forced into the space 67, the piston 61 is moved downwardly to an outer extreme position whereby the two wheels 1 and 3, provided they are not in mesh, are turned to such positions that coupling of the wheels can take place.

In a similar manner the wheels 2 and 3 90 are brought into engagement with one another, the wheel 3 being turned by the lever 26 while approaching the wheel 2. In case a tooth of the wheel 3 strikes a tooth of the wheel 2, the wheel 3 can be continually 95 moved by the lever 26 during the time that the wheels are in contact until a tooth thereof is brought into engagement with a tooth space of the wheel 2, provided the toothed wheels are spirally cut. In such case the 100 wheels will always come in contact with each other about in the same manner as two cylinders, viz., at a point coinciding with a straight line connecting the centers of the wheels. If on the contrary this device is 105 employed in spur gears, it may happen that two teeth will meet before reaching the said line. In such case the wheels cannot be turned until a tooth is brought into engagement with a tooth space, the turning being 110 prevented by the teeth meeting each other, and therefore the wheels are compelled to move apart, whereupon a new attempt must be made for setting the wheels.

In Figs. 5-7 the oil-starting device is 115 shown in detail.

Figs. 5 to 6 inclusive illustrate the different positions of the valve which controls the admission and exhaust of the actuating fluid which operates the various pistons.

In Figs. 5, 6, 7 and 8 the valve is shown in inoperative position. At this time it may be stated that the conduit 81 leads from the valve chamber 34 to the cylinder 73; the conduit 83 leads from chamber 34 to the cylinder 45; the conduit 89 extends from the chamber 34 to the cylinder 55; and the conduits 85 and 86 lead from the chamber 34 to the top and bottom of the cylinder 7. Fluid is admitted to the in- 130

terior of the valve through a passage 121 and the fluid is emitted through an exhaust passage 91.

The valve body 32 is provided at its upper portion with radial ports 87 and 88 and a semicircular slot 80. The lower portion of the valve is provided with a circumferentially extending recess 90 and a radial port 84. An axially extending recess 108 is also provided in the valve body and communicates with the recess 90. In the position shown in Fig. 7, the exhaust 91 is connected through the recess 90 in the slide valve 32 with the conduits 81, 83, 85 and 86, and the conduit 89 is connected through the recess 108 with the exhaust 91. By depression of the arm 30 investigation is first made whether the different wheels of the gearing are standing still. This position is illustrated in Fig. 9. In such position the slide valve 32 is depressed sufficiently into the cylinder so that the port 80 in the wall of the valve connects the conduit 81 with the interior of the slide valve which by means of the oil conduit 121 is in communication with the oil supply. If it is found that the wheels of the gearing are standing still, the arm 30 and the slide valve are turned to a certain extent and then depressed to the position shown in Fig. 12. In this position the oil conduit 83 leading to the piston 45 is connected with the pressure oil within the slide valve 32 by means of the port 80, the locking device of the gearing thereby being released. On further turning of the arm 30, the port 84 is brought into alignment with one of the conduits 85 or 86 and oil is admitted to the cylinder 7 at one side of its piston thus adjusting the wheels to forward running. At the same time the port 88 in the wall of the valve connects the interior of the latter with the oil conduit 89 thus setting the adjusting device 61-26 in operation.

For affecting backward running, the arm 30 and the slide valve are turned from the position shown in Fig. 8 in an opposite direction, oil then being supplied to the cylinder 7 at the opposite side of its piston for adjusting the wheels to backward running, and to the device 61-26 through the port 87. The slide valve 32 maintains always the connection between the outlet 21 and the side of the piston in the cylinder 7 not being connected with the oil supply. When the reversal is performed and the slide valve is turned back to sliding position, as in Fig. 7, the different oil cylinders are shut off from the oil supply and connected with the exhaust 91 in a course contrary to that followed when being connected with the oil supply.

The interior of the cylinder 32 containing pressure oil is connected by means of the exhaust 91 with the oil supply reservoir so

that the exhausted oil may be returned to its source.

It will be understood that the arrangement shown in the drawing is only an exceedingly detailed embodiment lending itself to a number of modifications while maintaining the characteristics of the invention. It is to be observed that instead of oil some other pressure medium such as water, steam, air or gas may be employed. In place of only one arm 30, two such arms positively interconnected, may be used.

What we claim as new and desire to secure by Letters Patent of the United States is:—

1. In toothed gearings, a reversing device comprising a member in gear with any one of the rotating parts of the gearing, motion transmitting members actuated by said member and locking members adapted to lock the reversing device and to be set in operation by said motion transmitting members.

2. A reversing device as set forth in claim 1 and further characterized by a rotary arm (30) adapted to be operated by pressure oil (90) and to act upon a piston (32) serving as a valve for said oil.

3. A reversing device as set forth in claim 1 and further characterized by the slide valve (32) being so arranged as to cause the oil to be supplied to cylinders actuating pistons which are connected with rotary members adapted to bear against friction tracks connected with any one of the gear wheels.

4. A reversing device as set forth in claim 1 and further characterized by a swingable frame (16) supporting one (2) of the wheels of the gearing, and a rotary disk (18) eccentrically supporting an intermediate wheel (3), the frame and the disk being operated by means of the slide valve (32) by the aid of pressure oil.

5. A reversing device as set forth in claim 1 and further characterized by the frame (16) and the disk (18) being connected with a shaft (13) in such manner that, upon the rotation of the shaft (13) in one direction, the intermediate wheel (3) is first disengaged and the wheel (2) thereupon brought into engagement with the driven wheel (1), whereas, upon rotation of the shaft (13) in opposite direction, the wheel (2) is first disengaged from the wheel (1) and the intermediate wheel (3) then coupled to both wheels (1) and (2).

6. A reversing device as set forth in claim 1 and further characterized by the shaft (13) being connected with a piston movable in a cylinder to which pressure oil is supplied at either side of the piston according to the direction of rotation of the arm (30).

7. A reversing device as set forth in claim 1 and further characterized by the frame (16) being operated by a cam (14) secured

70

- to the shaft (13), whereas the disk (18) is operated by a crank (12) attached to said shaft and by a rod (19) pivotally connected with said crank and said disk.
- 5 8. A reversing device as set forth in claim 1 and further characterized by each of the reversing device and the starting device of the driving medium being provided with a locking mechanism, the reversing device acting upon the locking mechanism of the starting device and the latter upon the reversing device.
- 10 9. A reversing device as set forth in claim 1 and further characterized by the arm (30) and a starting handle (56) being connected in such manner that only one of them is capable of assuming a position other than the normal one, the normal position of the handle (56) being that one in which the driving medium is shut off.
- 15 10. A reversing device as set forth in claim 1 and further characterized by the arm (30) and the handle (56) being locked in normal position by a common stop which, upon the movement of one of said members out of the normal position, is moved so as to lock the other member.
- 20 11. A reversing device as set forth in claim 1 and further characterized by the stop being retained, upon the movement of one of the members out of the normal position, in the position in which the other member is locked, so long as the latter assumes a position other than the normal one, for instance by the two members being provided with suitable bearing surfaces for the stop.
- 25 12. A reversing device as set forth in claim 1 and further characterized by a member which, on coupling the gear wheels, is adapted to move the same to a position in which the teeth of one wheel are situated just opposite the spaces between the teeth of the other wheel.
- 30 13. A reversing device as set forth in claim 1 and further characterized by the device for adjusting the gear wheels to correct position consisting of a piston (61) movable in a cylinder (55) and adapted to be actuated by pressure oil in the position of the slide valve (32) in which the reversing device is operated.
- 35 14. A reversing device as set forth in claim 1 and further characterized by the gear wheels to be coupled being provided with toothed rims (62) coöperating with levers (26) connected with the piston (61).
- 40 15. A reversing device as set forth in claim 1 and further characterized by the levers (26) being so arranged as not to co-operate with the toothed rims in one end position of the piston (61).
- 45 16. A reversing device as set forth in claim 1 and further characterized by the levers (26) being provided with sliding surfaces (68) adapted, on the movement of the piston (61) to one end position, to bear against the edge of an opening (69) in the cylinder so as to move the levers (26) out of engagement with the toothed rims.
- 50 17. In toothed gearing, a reversing gear adapted to mesh with a plurality of gears for reversing the movement of one of said gears, means for moving said reversing gear into engagement with said plurality of gears, and means for preventing movement of the latter means until one of said gears has ceased to rotate.
- 55 18. In toothed gearing, a reversing gear adapted to mesh with a plurality of gears for reversing the movement of one of said gears, means for moving said reversing gear into engagement with said plurality of gears, and means for alining a tooth of said reversing gear wth a tooth space of one of said plurality of gears.
- 60 19. A gearing of the kind defined by claim 18 having means for preventing movement of the reversing gear moving means until one of said gears has ceased to rotate.
- 65 20. In gearing mechanism, in combination a driving gear, a driven gear, and a reversing gear adapted to be thrown into mesh with the driving and driven gear when the direction of motion of the driven gear is to be reversed, means for ascertaining whether one of said driving or driven gears is rotating, means for bringing the teeth of one of said driving or driven gears into correct position to be engaged by the other one of said driving or driven gears, and means for moving said reversing gear into engagement with said driving and driven gears.
- 70 95 100 105 In witness whereof we have hereunto set our hands in the presence of two witnesses.
